UNITED STATES PATENT OFFICE.

SIDNEY A. GRANT, OF SPRINGFIELD, MASSACHUSETTS, ASSIGNOR TO THE UNITED STATES ENVELOPE MACHINE COMPANY, OF SAME PLACE.

ENVELOPE-MACHINE.

SPECIFICATION forming part of Letters Patent No. 432,749, dated July 22, 1890.

Application filed October 20, 1888. Serial No. 288,638. (No model.)

To all whom it may concern:

Be it known that I, SIDNEY A. GRANT, of Springfield, in the county of Hampden and State of Massachusetts, have invented a new and useful Machine for Making Envelopes and the Like, of which the following is a specification, reference being had to the accompanying drawings, in which—

Figure 1 is a plan of one form of machine embodying my invention, the greater part of the endless drying-chain with which my machine is preferably provided being removed for greater clearness. Fig. 2 is a front elevation with parts broken off. Fig. 3 is a rear elevation with parts broken off. Fig. 4 is a vertical section on line 4 4 of Fig. 1. Fig. 5 is a vertical section on line 5 5 of Fig. 1. Fig. 6 is a side elevation, partly in section. Fig. 7 is an elevation of the side opposite the side shown in Fig. 6. Fig. 8 is a sectional view of the creasing and gumming cylinders, and shows also a portion of the frame in which these cylinders are mounted. Fig. 9 is a section of one of the cylinders, showing it arranged to carry a type-plate. Fig. 10 is a section on line 10 10 of Fig. 8.

My invention is an envelope-machine which simultaneously creases and gums (and, if desired, prints) the envelope-blanks, one object of my invention being to produce machines of this sort which may be attended to in practice by unskilled or youthful attendants.

The features of my invention will be pointed out and claimed hereinafter.

While I prefer to use a slight projection on one cylinder and a slight depression on the other, it will be clear that a slight ridge forming a rectangular figure upon one cylinder and a slight groove forming a corresponding figure on the other cylinder will answer. I have tried both forms, but prefer the former, the only advantage of the latter being that the slight ridge forming the rectangular figure will make its own groove on a roll whose surface is sufficiently yielding.

In the drawings, which show one form of machine embodying my invention, (being the best form now known to me,) the device by which the blank is creased is made up of cylinders A A', one of the cylinders being provided with a land a and the other cylinder be-

ing formed with a depression a², adapted to receive the land, so that when the blank is pressed between the land and its corresponding depression creases are formed by the corners of the end and side walls of the land on the blank. Cylinder A is also shown as provided with gummers a', which are formed to correspond to the margin which is to receive the gum, and are conveniently supplied with gum by the gum-distributer a³, taking gum from fountains a⁴.

Folding-bed B receives the blank after it passes from between the cylinders A A', the blank being fed positively to the folding device, which may be of any suitable construction, but is preferably made up of the table B, folders b b² for the end flaps, and folder b' for the back flap. The folders b b' b² are actuated to fold the creased blank, and in the preferred form of my machine the positive feed of the blank from the gumming and creasing device to the folding device is accomplished not only by the creasing-cylinders, but also by the auxiliary disks a⁵.

One important feature of my construction is the combination, with a device for folding the end and back flaps, of a presser-foot, which, in the preferred form of my machine, not only holds the blank on the folding-bed while the end flaps are being turned, but also presses the back flap after it has been folded firmly on the underlying end flaps. This presser-foot is marked B'.

The envelope is moved positively out of the folding device by means of the reciprocating pusher B², which engages an edge of the envelope and shoves it off the folding-bed.

I prefer to feed the completed envelope from the folding device to a drying-chain D, the operation of which is hereinafter explained, and from the drying-chain the envelope is fed positively into a receiver R.

In the form of machine now shown, motion is communicated to cylinder A' from main shaft F through gears f f', shaft f², disk f³, rack f⁴, pinned thereto, guarded in box f⁵, and meshing with pinion f⁶ on shaft f⁷. The cylinders A A' are each provided with a pinion f⁸, and these pinions mesh together, so that the rotation of cylinder A' rotates cylinder A, which is mounted on shaft f⁹, mounted in a

bracket F', arms f¹⁰ of which are provided with eccentrics e e, (see Fig. 8,) so that when the bracket is rocked in one direction cylinder A is moved away from A', and when 5 rocked in the other direction is moved toward cylinder A'. The bracket is rocked by means of forked rod f¹¹, pivoted to an ear f¹² of bracket F' and projecting toward shaft f², on which a cam f¹³ (see Fig. 4) is mounted. 10 Forked rod f¹¹, provided with roll f¹⁴, co-operates with cam f¹³ to move cylinder A away from cylinder A'. The bracket F' is moved in the other direction by a spring f²². Cylinders A A' are closed to engage the blank to 15 crease and gum it, and when the blank is fed out of them are separated, so that the gummers do not come in contact with the companion roll, and they are held apart until it is time to feed another blank—that is, until 20 the folding operation is sufficiently advanced to make it practicable to feed another blank, and for this purpose I employ the dog f¹⁵, which is controlled by a treadle f¹⁶. Dog f¹⁵ is pivoted to the frame of the machine and is 25 moved out of the way of the bracket F' by pressing down on the treadle f¹⁶, and is returned into position under the bracket F by a spring f²³, (a portion of which is shown in Fig. 6,) the foot being then removed from the 30 treadle f¹⁶. The rotation of cylinder A rotates the gum-rollers through gears f⁸, f¹⁸, f¹⁹, and f²⁰. f²¹ is a doctor for the gum-roller. The cylinders A A', arranged as shown in the drawings, have a function as feed-rolls, but the 35 feed from the cylinders to the folding device is accomplished mainly by the disks a⁵, above referred to, and from these disks the blank is guided to the folding device largely by the disks b³ co-operating with corresponding disks b⁴, the disks b³ being mounted on arm b⁵, loose 40 on cross-rod b⁶. Disks b⁴ are mounted in the frame of the folding-bed B and are driven by gears b⁷, one of which meshes with a gear on one of the feed-rolls a⁵, which is driven by 45 gears meshing with a gear on cylinder A'. (See Fig. 4.) Rocker-arm b⁵ is moved by link b⁸, connecting the rocker-arm with rocker-lever b⁹, loose on shaft b¹⁷ and actuated by connecting-rod b¹⁰ and the cam l on shaft f², the 50 rod b¹⁰ having a roll 2 to engage the cam l against the force of a spring b¹¹, secured at one end to the frame of the machine and at the other end to connecting-rod b¹⁰.

When the blank is fed into place on table 55 B, the folder b is moved to engage an end flap and turn the end flap on the main portion of the blank. Motion is communicated to the folder b through link b¹², connecting the folder b, which rocks on shaft b¹³, to an ear on the 60 folder b², as indicated in dotted lines in Fig. 4, and this ear on b² (see dotted lines in Fig. 4) is connected by rod b¹⁵ to a cam on shaft f², the connecting-rod being provided with a roll 3, engaging cam 4, and being moved in 65 one direction against the force of spring b¹⁶ and being moved in the other direction by the spring b¹⁶, as will be readily understood with-

out further description by reference to Fig. 4. The movement of folder b thus combined with folder b² folds the end flaps of the blank, 70 the blank being held on the bed between the friction-rolls b³ and rolls b⁴ and also by the presser-foot B', which descends to clamp the blank upon the table B by the rocking of shaft b¹⁷, which is rocked by means of cam-rod b¹⁸, 75 fast to rocker-arm 5, and a cam x (shown in the dotted lines in Fig. 6) on the face of gear f', the rock-shaft being rocked against the force of spring b¹⁹, by which it is returned to place at the proper time. Rocker-arm 5 is 80 provided with a roller, (see dotted lines in Fig. 6,) which works with the cam x. (See Figs. 6 and 5.) The back-flap turner b', by means of which the back flap is folded, is moved to fold the back flap by the pusher b²⁰, 85 mounted in rack b²¹, meshing with pinion b²², mounted on shaft b²³, which is provided with a pinion b²⁴, meshing with rack b²⁵, which is reciprocated by means of a cam on the face of rotary disk f³, mounted on shaft f². As 90 pusher b²⁰ moves inwardly, it moves the back-flap turner b' on its rock-shaft b²⁷ against the force of springs with which that shaft is provided, the shaft being journaled in a recess in the folding-table B. The presser-foot B', which was lifted to allow the proper motion to flap-turner b', now descends, as above explained, and is afterward lifted by the rocking of shaft b¹⁷ in the other direction. Rocker-arm b⁵ and the friction-disks 95 b³, carried by it, are also lifted to allow pusher b²⁰ to move over the folding-bed and push the envelope into the drying-chain. As the envelope is pushed along, the edge of its sealing-flap comes against the sealing-flap turner 100 b²⁸, (mounted on rock-shaft b²⁹, which is rocked in one direction by cam-rod b³⁰, and cam 6 on the face of gear f', the cam 6 engaging roll 7 on rod b³⁰, and is rocked in the other direction by spring b³¹, with which cam-rod b³⁰ is 105 provided,) rides up the turner b²⁸, which is rocked to bend the sealing-flap along the line of its crease over toward the body of the envelope as the envelope is pushed along under the turner b²⁸ and off of the folding-table by the 110 continued forward movement of the pusher b²⁰. When the drying-chain D is used, the envelope is pushed off the folding-table into the chain, the members d of which open to 115 receive the envelope and then close to carry it to the receiver R, the chain D being mounted on a roll d' and a sprocket d², as will be readily understood by all skilled in the art, the shaft of the sprocket being provided with ratchet d³, with which a spring-controlled 120 pawl d⁴, mounted on arm d⁵, co-operates. Arm d⁵ is rocked by connections d⁶ d⁷ and crank-pin d⁸, rotating with shaft f². When the envelope has been carried into position for removal from the chain, it is seized by fingers r, 125 working in the chain, the members d of which loosen their grip on the envelope, as will be readily understood by those skilled in the art. When the envelope has reached the said po-

sition, the fingers are actuated by the rocker-arm r' , fast to rocker-shaft r^2 , to pull the fingers downwardly against the force of spring r^3 , and thereby to pull the envelope from the 5 chain into the receiver R . Rocker-shaft r^2 is rocked to accomplish this, and is provided with an arm r^{10} , connected by rod r^4 to an arm r^5 , mounted on shaft r^6 , the arm r^5 being adapted to engage the cam r^7 on shaft f^2 . 10 Receiver R is provided with a follower R' , which is moved in the receiver R by means of a rocker-arm r^8 , mounted on shaft r^6 and actuated by cam r^9 . The receiver R is also provided with a spring-controlled guard R^2 15 and with stationary guard R^3 .

Gear f^8 of cylinder A' meshes with gear a^7 , which meshes with a gear a^8 on ink-roller T , on which the ink-distributing rolls t rest. Ink is supplied to ink-roller T by a roll t' , which 20 comes in contact at proper times with ink-roller t^2 , rotating in fountain T' , the shaft of ink-roller t^2 being provided with a ratchet t^3 , which is engaged by a pawl t^4 , mounted on arm t^5 , which is connected by a link t^6 to an ear of the 25 flap-turner b^2 , the movement of which flap-turner causes the arm t^5 to move, and thereby to rotate the roller t^2 in the ink-fountain. The roller t' , which is intermediate the ink-roller T , and the roller t^2 , which rotates in the 30 fountain, are reciprocated between the two rollers, and are accordingly mounted in a bracket t^7 , which is rocked on shaft t^8 by an arm t^9 , controlled by a cam t^{10} , arm t^9 being provided with a roll. In order to secure a 35 thorough distribution of the ink on the ink-rolls, it is desirable to reciprocate one or more of them endwise, and in the machine shown the shaft of roller T is provided with a grooved hub t^{11} , in the groove of which is placed a 40 finger t^{12} , which engages cam 9 on disk f^3 .

When it is desired to print the envelope, the cylinder A' is provided with type—say an electro-type A^2 —which is preferably mounted on a reciprocating carrier a^{10} , so that the type-plate is in position to print when the block is 45 in its lowest position. The reciprocating carrier a^{10} is mounted in the cylinder A' , and is moved to move the type-plate into position to be inked by cams a^{11} on the shaft of the cylinder. The carrier a^{10} is moved against the force of springs a^{12} , and when the cams a^{11} are 50 in their inoperative position the carrier is returned into the position shown in Fig. 9 by the springs a^{12} . The shaft of cylinder A is journaled in the arms f^{10} of bracket F' , the eccentrics e of these arms fitting in bearings a^{13} , mounted in the frame of the machine. The bearings a^{13} and the bearings a^{14} of the 55 shaft of cylinder A' are mounted in an opening a^{15} , and adjusting-screws a^{16} are provided for regulating the space between the two cylinders, as will be readily understood from reference to Fig. 8, this regulation being to fix the cylinders at any desired distance apart, 60 and being wholly independent of the movement of the cylinders in relation to each other.

to vary the distance between them during the operation of the machine.

The machine is provided with table A^3 , having a number of guides a^{17} , by means of which the blank is properly guided to the cylinders A A' by the operator. Table A^3 is provided with stop-guides a^{18} , which prevent the insertion of a blank between cylinders A A' , except at the proper time, the guides a^{18} being 75 mounted on a leaf-spring a^{19} and projecting above the upper surface of the table in front of the rolls, except when depressed by the cross-bar of bracket F' striking pins a^{20} .

The operation of that form of my machine 80 shown in the drawings is as follows: Starting with the rack f^4 , bracket F' , and stops a^{18} in their highest positions (see Figs. 2, 4, and 6) motion is imparted to shaft f^2 from main shaft F and to disk f^3 , rotating with shaft f^2 and 85 carrying rack f^4 . As the rack descends, meshing with pinion f^6 , it carries the disk $9'$, which is fast to the pinion, and the pawl 10 , mounted on the disk, into the position shown in Fig. 7, and when the rack begins its upstroke the 90 pawl 10 engages the toothed disk 11 , fast to shaft f^7 , thereby rotating cylinder A' and compelling the rotation of cylinder A and parts connected therewith. The blank is presented by the attendant and properly gaged by the 95 stops a^{18} , one of its flaps projecting between the cylinders A A' ; but these cylinders are kept apart by the dog f^{15} until that dog is drawn away by the operator by means of treadle f^{16} , when the bracket F' is pulled down 100 by its spring f^{20} , thereby bringing the cylinders A A' together and nipping the front flap of the blank between them and also depressing the stops a^{18} , the rolls A A' being at this time stationary. The blank is carried through the 105 cylinders and fed by them positively to the auxiliary feed-disks a^5 , (which, together with the gum-distributors, are driven simultaneously with the cylinders A A' , as will readily be understood from what has been said 110 above,) and the auxiliary disks a^5 feed the blank to the disks b^3 b^4 , which guide and help feed the blank to the folding-table B . The feed begins when the rack f^4 is in its lowest position and continues during the upstroke 115 of the rack f^4 , so that the cylinders are intermittently rotated, thereby giving time to the attendant to put the blank in place to be seized by the cylinders A A' . As the rack f^4 begins its upstroke, the pusher b^{20} is drawn 120 back into the position shown in Fig. 5, and the end-flap turners b^2 are moved back out of the way of the blank which is being fed to the folding-table B . When the pusher has completed its back-stroke, the back-flap 125 turner b' is open—that is, thrown into the position shown in Fig. 5 by its springs. As the blank thus gummed and creased by the cylinders, and also printed, if desired, is fed forward on the folding-table, the arm b^5 , which 130 carries the friction-disks b^3 , descends to bring the disks in place to co-operate with the un-

der disks b^4 , and thereby guide the blank into place on the table B. When the blank has reached its proper position on the table, the feed ceases, because the rack f^4 then begins its downstroke and the presser-foot B' descends. As the presser-foot moves down, the end-flap turners b^2 move simultaneously to fold the end flaps of the blank, the end flaps being supported previous to folding by fingers projecting from the table. The presser-foot B' holds the blank in place while the end flaps are being turned. When the end flaps are folded and while the end-flap turners are yet on the blank, the presser-foot B' rises sufficiently to allow the pusher b^{20} to turn up the back-flap turner b' and fold the back flap over in place on the end flaps. The pusher b^{20} rides over the back-flap turner, lingering thereon, while the presser-foot B' descends on the flap-turner b' , and thereby presses the gummed flap firmly in place on the end flaps folded underneath. The arm b^5 , carrying the friction-disks b^3 , now begins to rise, and the end-flap and back-flap turners and the presser-foot move away from the folding-table nearly simultaneously, and the pusher, with its fingers 12 in grooves 13 in table B, begins to push the envelope toward the drying-chain. The seal-flap turner b^{23} now rises, the seal-flap being carried over the seal-flap turner by the forward motion of the envelope until the turner finally brings the seal-flap into position. The seal-flap turner is formed with a passage (see Fig. 5) for the pusher to allow the pusher to move through it and push the envelope into the drying-chain.

As the pusher forces the folded envelope into the drying-chain and before it is moved back, the rack f^4 reaches its lowest position, thereby bringing the cylinder into position to feed another blank.

What I claim as my invention is—

1. In an envelope-machine, the cylinders A A', in combination with folding mechanism, one cylinder having a land a and the other a depression a^2 to make the four creases between the flaps and the body of the envelope, substantially as and for the purpose set forth.
2. In combination with the cylinders A A', one having a land a and the other a depression a^2 , and actuating mechanism to intermittently rotate the cylinders, stop-guides a^{18} , and means, substantially such as described, (for example, bracket F', pins a^{20} , and springs a^{19}), for varying the position of the stops, the stops when in one position preventing the insertion of the blank between the cylinders and when in the other allowing the insertion of

the blank between the cylinders, all substantially as and for the purpose set forth.

3. In combination, creasing-cylinders A A', one having a land a and the other a depression a^2 , gummers a' , and gum-distributer a^3 , the gummers being mounted on creasing-cylinder A, substantially as and for the purpose set forth.

4. The improved means for creasing, gumming, and printing envelope-blanks, composed of cylinders A A', one having a land a and the other a depression a^2 , combined with gummers a' on one of the cylinders and a form A^2 on the other cylinder to simultaneously crease, print, and gum an envelope-blank, substantially as and for the purpose set forth.

5. In combination, feed-table A³, reciprocating stops a^{18} , and creasing-cylinders A A', one of the cylinders having an intermittent motion toward and from the other cylinder, and mechanism for depressing the stops a^{18} , and folding mechanism, all arranged and operating substantially as and for the purpose set forth.

6. In combination, a folding-table and folding mechanism, with feed-rolls and blank creasing and gumming cylinders, one of the cylinders having an intermittent motion toward and away from the other cylinder, all arranged to feed the creased and gummed blank positively to the folding-table, substantially as described.

7. In combination, folding-table B, flap-folder b' , flap-folder b' being mounted at one edge of table B, pusher b^{20} , and means (for example, rack b^{12} and pinion b^{22}) for reciprocating the pusher to turn the flap-folder b' and to move said pusher over the folding-table, substantially as and for the purpose set forth.

8. In combination, feed-table A³, reciprocating stops a^{18} , gumming and creasing rolls A A', stationary folding-table B, flap-folders b^2 b' , presser-foot B', reciprocating pusher b^{20} , and mechanism, substantially such as described, for actuating the same, the stops a^{18} being depressed to allow the operator to feed the blank to the creasing and gumming cylinders, the creasing and gumming cylinders simultaneously creasing and gumming the blank, the blank being fed positively from these cylinders to the folding-bed and removed positively from the folding-bed by the reciprocating pusher, all arranged and operating substantially as and for the purpose set forth.

SIDNEY A. GRANT.
